(57) **CLAIM**

The ornamental design for a patient controlled timed medication dispenser, as shown and described.

DESCRIPTION

FIG. 1 is an isometric illustration of a patient controlled timed medication dispenser of the present invention.

FIG. 2 is a front view of the patient controlled timed medication dispenser.

FIG. 3 is a rear view of the patient controlled timed medication dispenser.

FIG. 4 is a top view of the patient controlled timed medication dispenser.

FIG. 5 is a bottom view of the patient controlled timed medication dispenser.

FIG. 6 is a right side view of the patient controlled timed medication dispenser; and,

FIG. 7 is a left side view of the patient controlled timed medication dispenser.
